UNITED STATES PATENT OFFICE

1,928,423

WINDOW REGULATOR

Augie L. Hansen, Chicago, Ill., assignor to A. L. Hansen Mfg. Company, Chicago, Ill., a corporation of Illinois

Application November 12, 1931
Serial No. 574,478

2 Claims. (Cl. 268—128)

This invention relates to improvements in window regulators, and more particularly to devices for manually raising and lowering the windows of vehicle bodies.

5 The object of the invention is to improve upon the structural features of a similar mechanism disclosed in Letters Patent No. 1,827,746 granted to me on October 20, 1931, and among which may be mentioned the enclosure of the chain and 10 sprockets within a housing, thereby providing a self-contained unit more or less protected against accumulations of dust and dirt and proof against the undesired spreading of the grease or oil with which the chain is lubricated, to other parts of 15 the door.

A preferred embodiment of the novel features incorporated in the window regulating and operating unit is disclosed in the accompanying drawings, in which

20 Figure 1 is a general view in elevation of a door frame for a vehicle body showing the complete installation;

Figure 2 is a view in vertical section through the door as taken on line 2—2 of Figure 1;

25 Figure 3 is an enlarged detail view of the outer or crank side of the regulator unit;

Figure 4 is a similar view of the inner or opposite side of the unit;

Figure 5 is an enlarged detail view of the unit 30 in vertical section as taken on line 5—5 of Figure 6;

Figure 6 is a view in side elevation of the unit, a part of the housing being broken away;

Figure 7 is an enlarged detail view in section 35 through the crank operated sprocket and clutch mechanism as taken on line 7—7 of Figure 1;

Figures 8 and 9 are detail views of the clutch mechanism as taken on lines 8—8 and 9—9, respectively, of Figure 7; and

40 Figure 10 is a perspective view of the window connecting member of the unit.

Referring to Figures 1 and 2, the regulator is shown as applied to a door frame 1 of a vehicle body of any standard construction and designed 45 either for commercial or pleasure vehicles, the chief distinction being the fact that the body of a pleasure vehicle is more elaborately finished and heavy plate glass panels are used for the windows. As shown, the upper half of the door is 50 provided with a square opening, the lower half enclosing a hollow space or well in which the regulator is housed and into which the window is lowered. For the purpose of this disclosure, the inner edges of the vertical rails 2, 2 of the window 55 opening are grooved or rabbetted as at 2^a to re-

ceive the sliding window sash 3 consisting of a frame 3^a and a glass panel 3^b. The window slides in the rabbets or grooves 2^a, 2^b in the sides of the door frame, the top rail 4 of said door frame preferably having a slot 4^a extending vertically through it to permit the window to be inserted or removed through the top, as shown in Figure 2.

The door frame is divided transversely by a cross rail 5, the space above forming the window opening and the space below providing the well into which the sash is lowered by the operation of the regulating unit, extending vertically and centrally of the lower half of the door frame and fastened at its ends to the inner face of the cross rail 5 and the bottom rail 6 of the frame as shown in Figures 1 and 2.

Referring to the regulator unit per se, the same comprises a relatively narrow elongated casing or housing 7 which substantially encloses a chain and sprocket assembly, consisting of a pair of sprocket wheels 8 and 9 journaled at the upper and lower ends of the housing, respectively, and an endless chain 10 extending the length of the casing and around the sprockets. The upper sprocket 8 is fixed to a stub shaft 11 forming its journal, one end of the shaft being extended beyond the inner wall of the housing and on this end is mounted the operating crank handle 12 which is located on the inside of the door just below the window opening after the unit has been installed.

The casing or housing 7 is made up of two sheet metal members or parts, one a shallow channel-shaped member 13 and the other a flat strip 14 slightly narrower than the first member and permanently fixed thereto to close the open side of the space included by the channel member.

The channel member is first blanked out from sheet metal and then formed to shape in the usual manner, and in the blanking and forming operation pairs of laterally extending wings are provided at each end which form transverse end plates 13^a, 13^b, with screw holes punched therethrough, whereby the assembled unit is attached to the door frame (Figure 3). Throughout the length of the channel member between the end plates 13^a, 13^b, the marginal portions are bent at right angles to form the side flanges 13^b, 13^a about one-half an inch in width. And finally near the lower end of the channel member and centrally of its main wall portion, an elongated ear 15 is stamped from the blank being severed about three edges, but having integral connections along its base edge, so that the ear extends longitudinally

toward the upper end of the housing. The purpose of this ear will be presently explained and in connection with the assembly operation.

The other member or strip 14 which completes the housing is somewhat simpler in its formation. Its top edge portion is bent in L-shape to provide a flange 14^a which is welded in flatwise contact to the upper end plate 13^a of the channel member and a transverse web 14^b which determines the depth of the space within the housing. A short distance below the flanged end of the strip is provided a round hole 14^c forming a bearing for the end of the stub shaft, and just below this hole is an ear 16 similar in every respect to the one formed in the channel member, except that its free end is directed toward the lower end of the housing. Another ear 16 is punched in the strip member approximately midway of its length, and finally at its lower end is a narrow slot 17 elongated longitudinally, this slot forming a bearing for the lower sprocket which, as will presently be noted, is shiftable under spring pressure to maintain the chain under uniform tension. (Figure 5).

Now, the housing is assembled by joining the channel and strip members together through the medium of the several ears 15 and 16, which are bent during the forming operation to provide transverse spacing webs 15^a and 16^a and parallel offset tongues 15^b and 16^b which bear flatwise against the opposite wall and then in the assembly operation are spot-welded as at *w*, the flange 14^a at the upper edge of the strip member 14 being spot-welded in the same operation.

Manifestly, all of the moving parts are assembled in place before the members of the housing are welded together. Thus the stub shaft 11 on which the upper or driven sprocket 8 is loosely mounted, is inserted endwise through the aligned bearing holes in the channel and strip members 13 and 14, the former being located at the center of a bulbous projection 18 pressed outwardly from the front wall of the channel member. (Figure 7). The lower sprocket 9, however, does not have direct bearing in the housing, but is journalled at the lower end of a U-shaped yoke 19 which straddles the sprocket and supports its journal pin 9^a, the latter having an extended end which rides in the slot 17 in the strip member 14 of the housing. Extending from the base of the U-shaped yoke is a rod 20 projecting lengthwise of the housing toward its upper end, the end of said rod passing through a hole 21 punched in the transverse web of the ear 15 stamped from the channel member 13 near its lower end. And finally, a coil spring 22 surrounds the rod and bears at its upper end against the web 15^a of the ear 15. Thus the lower sprocket is free to shift against the pressure exerted by the spring in a direction to keep the chain 10 under tension. The chain is of a suitable type with links to engage the teeth of the sprocket wheels, and traveling in either direction by the turning of the crank transmits an upward and downward movement to the window through suitable connecting members, one being a part of the regulator unit and the other attached to the lower edge of the window.

The connecting member of the regulator unit is a metal slide 23 forming a part of the chain, and at the same time mounted to slide lengthwise along one side of the housing and within a slot 24 separating one edge of the strip 14 and the inner face of the adjacent flange 13^b of the channel member 13. This connecting member 23

is preferably stamped from sheet metal and consists of several integral parts as follows: (Figure 10) The base of the member has the form of a link 24 with hooked ends which connect the free ends of the chain. Projecting outwardly from one edge of the link portion is a flat lug 25 formed by bending a strip-like section of the metal over and inwardly upon itself so that the projection has the form of a flattened loop. And finally at the lower end of the down-turned portion of the lug is an integral guide plate 26 bent at right angles thereto and extending laterally in both directions therefrom, and at the extremities of this guide are clips 26^a, 26^b which are bent transversely over the ends of the guide and in a direction away from the lug 25. Thus the base portion of the connecting member travels in line with the chain with the lug 25 projecting outwardly from the slot 24 and slides lengthwise thereof. The guide plate 26 slides along the under edge of the wall member 14 of the housing with clips engaging the edges, so that a smooth sliding movement is effected. Connection with the window sash 2 is made through a bracket 27 attached to the lower edge thereof, and having a depending portion in which a slot is formed to receive the lug 25 of the connecting member 23.

Manifestly with such an arrangement, the connecting member can only move in a straight line upwardly and downwardly in the slot 24, carrying the window with it through the connection between the projection of the regulator unit and the bracket 27 mounted centrally of the lower edge of the window sash, the latter permitting detachable connection with the lug 25 so that connections can be conveniently made during the assembly of the door, and also to permit the window to be detached and removed without disassembling the door frame in case of breakage and replacement.

In the preferred construction of the regulator unit, the upper sprocket wheel 8 is not directly connected to the stub shaft 11 but turns loosely thereon, the movement from the crank handle to the sprocket wheel being transmitted through a clutch mechanism which is introduced for the following reasons: If the crank were directly connected with the sprocket, it follows that the window could be opened and closed either by turning the crank or by applying a lifting or depressing force directly upon the window, with the result that the window could be readily lowered from the outside and the interior of the vehicle made easily accessible even though the door were locked. In other words, the window would be free running either by turning the crank or by raising or lowering the window itself, so that it is the function of the clutch to lock the unit against movement in a downward direction either by pressure applied direct to the window or by gravity due to the jarring or vibration of the vehicle in motion.

Referring to Figures 7, 8 and 9, the clutch consists of a disc 28 fixed to the stub shaft 11 carrying the handle, said disc being located within a cup-like member 29 on the inner face of the housing and partially sunk within the recess formed by the dome-like projection 18 in the wall of the housing. This disc has a pair of diametrically opposed fingers 28^a, 28^b extending parallel with the inner end portion of the stub shaft and toward the sprocket 8, their ends engaging a complementary pair of arcuate slots 8^a, 8^b passing through said sprocket inwardly from the periphery thereof. These slots extend through arcs

of approximately 90° each, and permit a relative rotation between the sprocket and the shaft 11 of about 90° in both directions. Surrounding the fingers of the disc 28 and housed within the cup member 29 is a coiled spring 30 having its inner end 30^a bent radially inward at right angles into the path of the fingers of the disc and its outer end is also bent at right angles but parallel to its axis to form a lug 30^b which engages a hole 8^b 5 in the sprocket 8. Now, this spring forms a resilient connecting member between the crank operated shaft 11 and the sprocket 8, and its action will be understood from the following:

Assuming first that the crank is turned in either direction to raise or lower the window panel, it will be apparent that in either case the disc turning with the shaft will engage the inner end of the spring and tend to rotate it in the same direction and the spring in turn will tend 10 to revolve the sprocket in the same direction. There is a certain load on the sprocket due to friction, so that regardless of the direction of turning, the force exerted on the spring is such that it is contracted appreciably, that is, in an amount sufficient to release its normal frictional 15 contact with the annular wall of the cup member, and it then is free to revolve with the shaft and the sprocket member. Similarly if a force is applied to the window panel in a direction to raise it, this force is transmitted to the sprocket to rotate it in a clockwise direction, and so in a direction to contract the spring 30, thus permitting the window to be raised. But, if the force is applied to the window in a direction to lower it, the rotation transmitted to the sprocket is in the reverse direction, and the effect of this rotation is to release the spring, whereupon it is free to expand and thus frictionally grip the wall of the cup member much after the manner of an internal expanding brake band and drum, and the

harder the force is applied, the greater the frictional locking force applied by the spring. Consequently, the sprocket is free to turn with the crank, except when a force is applied to the window sash to lower it, and then the frictional locking action takes effect immediately and effectively to prevent the movement of the window. 80

The regulator unit as thus constructed and assembled affords a very compact and sturdy mechanism, with all moving parts effectively concealed, 85 protected and supported for free and noiseless operation.

I claim as my invention:

1. A window regulator comprising an elongated metal casing adapted to be fixed at its ends in a door frame, sprocket wheels journaled in said casing adjacent its ends, an endless sprocket chain carried by said wheels, and means for connecting said chain with a sliding window in said frame, including a lug attached to said chain and projecting through a slot in said casing for sliding engagement therewith, and guide members spaced from said lug and having sliding engagement with one edge of said slot. 90

2. A window regulator comprising an elongated metal casing consisting of spaced front and rear walls and narrow side walls, sprocket wheels journaled within the ends of said casing and a chain on said sprocket wheels, a connecting member for attaching a sliding window to said regulator comprising a portion insertable in said chain and having a projecting flat lug adapted to have sliding engagement in a narrow slot extending longitudinally along one side of said housing, and a guide integral with said connecting member and 105 having sliding engagement with one edge of the casing along said slot at a point spaced from said lug. 110
